CLAIM

The ornamental design for a deodorant cap as shown and described.

DESCRIPTION

FIG. 1 is a top perspective view of a deodorant cap on a deodorant stick showing my new design;

FIG. 2 is a top perspective view thereof;

FIG. 3 is a bottom perspective view thereof;

FIG. 4 is a top plan view thereof;

FIG. 5 is a front elevation view thereof; and,

FIG. 6 is a left side elevation view thereof.

A design rear elevation view has been omitted, as it is the same as the front elevation view of FIG. 5.

A design right side elevation view has been omitted, as it is the same as the left side elevation view of FIG. 6.

The portion of the deodorant cap depicted in the figures in broken lines forms no part of the claimed design.
